UNITED STATES PATENT OFFICE.

WILLIAM DUNHAM FARREN, OF DANVILLE, CALIFORNIA.

RAILWAY-SEMAPHORE, &c.

SPECIFICATION forming part of Letters Patent No. 704,015, dated July 8, 1902.

Application filed July 24, 1900. Serial No. 24,674. (No model.)

To all whom it may concern:

Be it known that I, WILLIAM DUNHAM FARREN, a citizen of the United States, residing at Danville, in the county of Contra Costa, State of California, have invented a new and useful Railway-Semaphore, of which the following is a specification.

This invention relates to improvements in railway-semaphores. Its objects are to simplify, cheapen, and generally improve the construction of such devices, to render them durable, automatic, and reliable in operation, to give three separate movements or positions of the one semaphore-arm, and by the agency of red, green, and clear disks to indicate the same positions at night.

With these objects in view my invention consists of improved construction, arrangement, and combination of parts composing a signal of this class, which will be hereinafter fully described and afterward specifically pointed out in the appended claim.

In order to enable others skilled in the art to which my invention most nearly appertains to make and use the same, I will now proceed to describe its construction and operation, reference being had to the accompanying drawings, forming a part of this specification, of which—

Figure 1 is a side view of my improvement, showing the several positions of one of the arms in dotted lines. Fig. 2 is a plan view, the arm being in an extended position. Fig. 3 is a detail vertical section of the upper end 35 of the post, showing the manner of operating the lamp.

In constructing a signal in accordance with my improvement I employ a hollow post A, having its upper end terminating in a hood 40 or case a, which is provided with openings through which the light shines. In the upper portion of the hood is journaled a horizontal shaft a', upon the outer end of which is secured the semaphore-arms B and C, each 45 having a series of apertures b and c, respectively, which are adapted to be brought into register with the opening upon either side of the hood. The outer ends of the arms are provided with the usual semaphore-boards B' 50 and C', while their opposite ends are provided with counterbalance-weights, as shown at B²

and C². Each arm is provided with a vertically-extending arm or rod b' and c', to which is attached cords, whose opposite ends are connected to cranked lever and by which the 55 arms are raised or lowered.

The lamp or lantern F is adapted to operate within the post, and in order to provide a simple means for raising it I attach to the bail of the lamp a cord G, which is passed up 60 over the shaft a' and then carried down to within easy reach of the operator, when it is securely fastened within the post.

In order to obtain access to the lamp, I provide the lower end of the post with a door A², 65 and the upper end of the post is preferably provided with guides A³, which may be secured in any suitable manner.

The particular advantage of arranging the arms as described is to enable the operator 70 to easily and positively display the following signs: first, a horizontal position, meaning to "stop;" second, when the arms are arranged upon an angle of forty-five degrees means to "slow down," "caution," "block or track occupied," while the third position, in which the arm hangs perfectly vertical, indicates a 75 "clear track."

The arms may be painted red and green, as usual, while the apertures are provided 80 with similar-colored lines in order to make the signals discernible at night.

From the foregoing the simplicity and advantage of my improvement will be readily apparent, and it will also be observed that 85 the arms by one movement of either lines will be operated simultaneously, thus rendering the signal discernible from either side.

Having fully described my invention, what I claim as new, and desire to secure by Letters 90 Patent of the United States, is—

The combination of a hollow post whose upper end terminates in an enlarged hood-section and whose opposite faces are provided with apertures, a shaft journaled in the said 95 hood and having its ends projecting through the hood, semaphore-arms secured to the ends of the shaft, the said arms having a series of openings arranged intermediate its ends, one end of the arm having a counterbalance-weight secured thereto, rods projecting from the arms, cords connected to the rods for op-

erating the arms, a lantern arranged within the hood and having a cord connected thereto which passes up over and around the said shaft and suspends the lantern in an elevated 5 position, the lower end of the cord being secured to the post, substantially as shown and described.

In testimony whereof I have signed my name to this specification in the presence of two subscribing witnesses.

WILLIAM DUNHAM FARREN.
